UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

METHOD OF FEEDING PAPER.

1,170,210.

Specification of Letters Patent.

Patented Feb. 1, 1916.

Original application filed April 3, 1909, Serial No. 487,629. Divided and this application filed May 23, 1914. Serial No. 840,488.

To all whom it may concern:

Be it known that I, HENRY A. WISE Wood, a citizen of the United States, residing at New York, in the county of New York and 5 State of New York, have invented a new and useful Method of Feeding Paper, of which the following is a specification.

This is a division of my application for patent on a paper lubricating device for 10 printing press, filed April 3, 1909, Serial No. 487,629.

The object of this invention is to improve the operation of printing presses, particularly those which print from a continuous 15 strip or web. In machines of this character, the web of paper is led over a number of rolls, the surfaces of which move at the same speed as, or slightly greater than, the paper. When the printed surface of the web turns 20 over a roller or cylinder which moves therewith, the freshly printed surface of the web sticks to the surface of the roller or cylinder and considerable strain has to be put upon the web to pull the same from that surface, 25 although the surface of the roller moves with the web. These factors render it necessary to put the web under considerable tension, which tension increases as the speed increases and which may become so great as 30 to break the web. These factors therefore limit the speed of the machine and tend to damage the impressions. I have discovered that these factors can be largely eliminated 35 by interposing a thin film of air between the web and the rotary surfaces over which it runs and which normally support it and remain in contact with it for an appreciable time, which film acts as a cushion or lubricant and assists the web in its travel over the 40 guiding and directing surfaces. Not only does this film of air act to help the web in its passage through the machine, but it helps to prevent smutting of the impressions as the same obviates a hard or intimate contact of the web with the various surfaces. The film of air also acts to help dry the ink. 45 This thin lubricating film of air to prevent hard rubbing and smutting may be obtained by perforating the surfaces of the guiding rollers, cutting and collecting cylinders, etc., with minute holes and by forcing air under low pressure out through these holes.

Another difficulty which is encountered in

running a web of paper rapidly through a printing machine is that the friction is apt 55 to generate static electricity which causes the paper to cling or adhere to the surfaces over which it passes. This also increases the tension and the liability of the web to tear or break. This factor can be largely over- 60 come by the air lubricating method herein described and when extreme electrical conditions are encountered, steam or water vapor can be introduced into the air which is forced through the apparatus so that the 65 vapor will tend to dispel the electrical charges.

My invention can be worked out in many detailed forms and I have shown in the drawings, forming part of this application, 70 one construction by which the principle of my invention can be practised in connection with a standard newspaper web printing press.

Referring to the drawings and in detail, 75 Figure 1 is a diagrammatic side elevation of a web printing press and folding machine illustrating diagrammatically the application of my invention thereto; Fig. 2 is a side elevation on an enlarged scale showing part 80 of the pipe line that is employed to direct air to the inside of the various web guiding surfaces; Fig. 3 is a sectional view illustrating a construction which may be used so that air can be introduced into one of the 85 journals of the rollers; Fig. 4 is a view of a shield which may be employed with a guiding roller to cover up the surface thereof which does not contact with the web, and Fig. 5 is a modification hereinafter described 90 showing a different way by which the thin lubricating film of air can be introduced between a guiding surface and a web.

Referring to the drawings and in detail, 95 it will be seen that I have shown my invention as applied and adapted to an ordinary two-deck newspaper printing machine. The web *w* for the lower deck is drawn from a web roll *W*, is led around guide roller 11, adjustable guide roller 12, guide roller 13, 100 guide roller 14, around the first impression cylinder *A*, around the second impression cylinder *B*, around guide roller 15 to guide roller 16. The web is slit into two sections by a slitter *S* and a line of paste may be applied to the center of one of the two sections 105

of the web at this point if desired. From this point the section of the web is deflected laterally over an angle or turner bar 17 and then is brought back into the path of the section w' of the web by another angle bar 18, whereby the two sections of the web are associated or plicated. From this point the plicated webs are led around a guide roller 19, around an adjustable guide roller 20 to a 10 guide roller 21 and then down over a longitudinal former F. One or more decks or similar printing presses may be arranged above the one previously described and one section of printed web w^3 therefrom may be 15 led directly to the guide roller 21 and the other section w^4 therefrom after passing around roller 160, adjusting roller 161, roller 16 and the angle or turner bars of this press, may be led around adjustable 20 guide roller 22 and roller 23 to the roller 21. Thus the web or webs printed and associated in the second deck can be associated with the web or webs printed and associated by the lower deck. The associated webs are drawn 25 down over the former by rollers 24-24 and 25-25 and thus are given a longitudinal fold. From these rollers the associated and folded webs are drawn between a folding and collecting cylinder G which may be of 30 any of the ordinary constructions and coöperating cutting cylinder. The collecting cylinder G may be provided with rotary folders which may act to give the severed section of the webs a transverse fold in be- 35 tween the folding rollers 26-26, from which point the folded product is delivered by a rotary deliverer Q operating in the usual way. Coöperating with the first impression cylinder A is a plate or printing cylinder C 40 and coöperating with the second impression cylinder B is a plate or printing cylinder D. Coöperating with each of the printing cylinders is an ink drum E from which ink is taken to the plate cylinders by the usual form inking rollers. Coöperating with this 45 drum is an ordinary ink supplying mechanism consisting of an ink fountain, vibrating ductor roller and ink distributing and spreading rolls.

50 As thus far described, the parts referred to are intended to designate and particularize the instrumentalities which go to make up a newspaper web printing press.

It will be seen that as each web runs 55 through the machine it contacts with a number of surfaces which move with it. Thus in the case of the web in the complete lower press, the same has to run substantially with the following different rotary surfaces 60 or parts outside of the impression cylinders A and B; to wit, rollers 11, 12, 13, 14, 15, 16, 19, 20, 21, 24-24, 25-25, cylinder G and rollers 26-26. Obviously, this holds the web back, puts the same under tension and 65 smuts the impression. The freshly printed

surface of the web is particularly apt to stick or cling to the surfaces with which it contacts in its path beyond the roller 15. The engagement of the web with the surfaces specified also is apt to generate static 70 electricity which causes the web to cling to the surfaces. These factors additionally cause a drag on the web and smut the freshly printed impression. These points are thus described in detail in order that it 75 may be clear what considerable factors of resistance and smut the web encounters in even the simplest form of web printing press. I have discovered that these factors, which are largely the limiting factors 80 of the speed of the web presses of to-day, can be largely overcome by blowing or forcing a thin film of air between the rotary surfaces over which the web runs and the web itself. This film will cushion the web or will 85 form sort of a lubricating engagement between the web and the surface and will prevent intimate contact of the web therewith. This air film or lubrication is particularly 90 advantageous in preventing offset on these surfaces which move with the web.

The invention can be practised in very many ways and I have shown the same as practised in connection with the web press previously described by providing a source 95 of air pressure; by perforating the rollers or cylinders over which the web passes and connecting the source of air pressure to the journals of the rollers or cylinders; by making the former double walled; providing the 100 surface thereof over which the web runs with minute perforations; and connecting the space between the walls of the former with the air supply. In this way, the advantages previously pointed out are easily 105 obtained. The following is a detailed description of this arrangement. M designates a suitable motor which may be the motor which drives the press or any other source of power. This motor is connected to operate an air pump P of any kind. Extending from the eduction of the air pump or from an interposed storage tank T is a pipe 30 which may rise vertically of the press. Connected to the pipe 30 are pipes 31 which 110 extend along horizontally at the side of each press, as many pipes 31 being employed as there are decks to the machine. Extending from the pipe 31 are branches 32 each of which has a valve 33. A branch 32 is provided for each of the rollers 11, 13, 14, 15 and 16. These branches connect to boxes 34 in which the journals of the guides are journaled, as shown in Fig. 3. The guide rollers are made hollow as shown in Fig. 3 115 and the journal of each one thereof on the side of the machine where the pipe line is arranged is made hollow or in the form of a tube so that the air will be forced inside of the roller. Each of the rollers is pro- 120 125 130

vided with a large number of minute perforations V, as indicated in Fig. 3, so that the air will be forced out between the web and the surface of the guiding roller. If 5 desired, a shield or partially cylindrical plate X may be arranged to bear on the roll, as shown in Fig. 4, to leave exposed only enough surface of the roll for the contact of the web therewith so that there will 10 be no waste of air. This shield may be faced with cloth or any suitable surface so as to close tightly the perforations in the roller which are not engaged by the web. The pipe-line 31 is extended up at the end of the 15 machine as at 37 and is provided with valved branches 38 which communicate with the journals of the collecting cylinder G with the journals of the folding rollers 26—26, and with a journal of the rotary deliverer 20 Q. These rollers and cylinders are made hollow and the surfaces of the same are provided with minute perforations as previously described. Shields may be used around these rollers or cylinders if desired 25 to expose only the perforations therein which are in engagement with the web. The perforations in the various cylinders and rollers may be proportioned and distributed over the surfaces so as to lift or separate the 30 web therefrom evenly or as desired from the surfaces.

In some cases it may be desirable for the 35 reasons previously stated, to introduce water vapor into the air which is forced out through the parts of the machine. This can be done by supplying steam or water through a pipe 42 to the pump P. Or if it is desired to supply the water vapor or steam to any one part as to the particular roller 40 or surface, the same can be accomplished by introducing a nozzle, as indicated at 43 in

dotted lines in Fig. 3, into the branch pipe communicating with the particular surface.

In some cases, instead of introducing the film of air into the inside of the roller and letting the same out through perforations 45 in the periphery thereof, the film of air can be introduced by a suitable nozzle or nozzles 45 arranged to blow a film or blast of air between the surface of the web and the 50 guiding surface as they move either or both toward or from each other, as shown in Fig. 5.

Many other different devices, apparatuses and connections can be devised by a skilled 55 engineer for applying the principle of my invention to different forms of printing presses. I have only shown in this application what I now believe to be the best form for practising the invention.

The details and arrangements herein shown and described can therefore be greatly altered without departing from the broad scope of the invention as expressed in the claim. Therefore I do not wish to be limited 65 to all the details of construction shown or to the particular form of the device herein shown and described, but

What I do claim is:—

The method of assisting the travel of 70 paper, which consists in forcing a lubricating fluid such as air between the paper and a surface or surfaces over which the same passes, and introducing water vapor into the air.

In testimony whereof I have hereunto set my hand, in the presence of two subscribing witnesses.

HENRY A. WISE WOOD.
